JOHN G. ZUBER, OF CHICAGO, ILLINOIS.

VARIABLE-DELIVERY PUMP AND INJECTOR.

1,224,589.

Specification of Letters Patent. Patented May 1, 1917.

Application filed May 12, 1916. Serial No. 97,047.

To all whom it may concern:

Be it known that I, JOHN G. ZUBER, a citizen of the United States, and a resident of Chicago, county of Cook, and State of Illinois, have invented certain new and useful Improvements in Variable-Delivery Pumps and Injectors, of which the following is declared to be a full, clear, and exact description.

10 This invention relates to variable delivery pumps and injectors, and its main objects are, to provide improved means for injecting liquids (such for instance as liquid fuel) into engine cylinders or other chambers; to 15 provide for accurate and controllable variations of the volume of liquid delivered by the device; to provide improved means for delivering measured quantities of liquid at very rapid intervals, and to otherwise improve 20 upon the efficiency of variable delivery pumps and injectors. With these and other objects in view, this invention consists in the several novel features hereinafter fully set forth and claimed.

25 The invention is clearly illustrated in the accompanying drawing, in which:—

Figure 1, is a view partly in end elevation and partly in cross section of a variable delivery pump and injector, embodying a 30 simple form of the present invention, the line of section being indicated at 1—1, in Figs. 2 and 3; Fig. 2, is a vertical section taken on line 2—2, Fig. 1; Fig. 3, is a horizontal section taken on line 3—3, Fig. 1, and 35 Fig. 4, is a vertical cross section of a slightly modified form of the invention.

Referring to said drawing, 10, designates 40 a case in which are contained the operative parts of the device, and if desired said case may be filled or partly filled with a lubricant for the purpose of lubricating certain moving parts.

On the inner side of one wall 11, of the case are formed three cylinders or hollow 45 bosses 12, 13, 14, the bores of which receive plungers 15, 16, 17, that are reciprocated back and forth in said bosses in timed relation to each other by shafts 18, 19, 20, and cams, cranks, or eccentric connections 21, 22.

50 The outer ends of the plungers 15, 17, are seated in bearings formed in lugs 22^a, carried by the wall 23, of the case or in any other convenient manner as desired. The connections between the shafts 18, 20, and 55 plungers 15, 17, may, for the sake of obtaining the greatest accuracy in measuring the

quantity of liquid to be delivered, comprise scotch yoke devices as shown, and in the drawing the plungers 15, 17, are shown as formed with yokes 24, in which are guided, 60 slide blocks 25, that receive eccentrics 26, mounted on or carried by the shafts 18, 20. The plunger 16, is shown as formed with a head or enlargement 27, upon its outer end, which is struck by the cam 22, on the cam 65 shaft 19, otherwise said plunger 16, is freely movable in the bore of its cylindrical boss. Each of said bosses is provided on its end with a stuffing box 28, to make tight a joint around the plunger and prevent leakage of 70 the liquid at that end of the boss. The cam shaft 19, is the main or driving shaft of the device and is driven from the motor or other device upon which it is used and in timed relation thereto, and the shafts 18, 19, 75 20, are operatively connected to rotate in unison and at the same speed, spiral gears 29, 30, 31, being shown in the drawing for accomplishing this result. The gears 29, 31 are fast upon their shafts 18, 20, but the 80 gear 30, is slidably mounted on its shaft 19, and is connected to it by a key 32, which runs in a key seat 33, in the shaft. A fork 34, on a rod 35, and engaging with a grooved neck 36, on the gear 30, provides convenient 85 means for shifting said gear on the shaft.

One of the gears 29, 31, is a right hand spiral tooth gear and the other a left hand one, and the gear 30, is formed with right and left hand spiral teeth, the teeth of one gear 29, meshing one set of teeth of the gear 30, and the teeth of gear 31, meshing with the other set of teeth on said gear 30; the result is that rotation of the cam shaft and the gear thereon drives the gears 29, 31, 90 and shafts 18, 20, in the same direction, at the same speed, and by shifting the gear 30, lengthwise on its shaft, the shafts 18, 20, are thereby turned in opposite directions 95 whereby the major axes of the eccentrics may be moved from a position in alinement with each other to any angular position with respect to each other, the purpose of which is to control the amount of liquid delivered 100 to the ejection chamber of the pump.

The bores 12^a, 14^a, open directly to an inlet passage 37, which connects with the liquid supply pipe 38, there being a check valve 39, in the inlet passage 37, between the supply pipe and bore 14^a, of the cylindrical boss 14, opening toward said bore. 110 The inlet passage 37, leads to the bore 13^a,

of the ejection cylinder, by way of a port 40, (see Fig. 2) at which port 40, is a check valve 41, opening toward said ejection cylinder 13. From the bore 13^a, of the ejector cylinder leads a discharge port 42, which is closed by a suitably operated valve 43, and said discharge port 42, communicates with the discharge or delivery pipe 44. For convenience, the valve 43, is shown as comprising a check valve, although it may be mechanically operated to open and close, and when a check valve is used the spring 43^a, thereof has sufficient tension to hold the check valve 43, closed during the charging strokes of the plungers 15, 17—that is while they are charging the chamber of the cylinder 13, and the discharge port 42.

When used for feeding liquid fuel to internal combustion engines the supply pipe is connected with a source of liquid fuel, and the discharge pipe connected with the combustion chamber or cylinder of the engine; the cam shaft is driven from said engine to run at the proper speed relative thereto. In operation, the cam shaft 19, is driven in the direction of the arrow (see Fig. 1) and the shafts 18, 20, driven in the direction of the arrows, through the instrumentality of the spiral gears 29, 30, 31, thereby imparting reciprocal movements to the two plungers 15, 17. The drawing shows the charging plungers 15, 17, on their suction strokes; liquid fuel is drawn into the bores of the cylinders 12, 14, filling the space behind the plungers and at the same time the liquid fuel flows past the check valve 39, into the inlet passage 37, thereby filling it. On their charging stroke the plungers force the amount of liquid fuel, which was admitted to the inlet passage, through the port 37, past the check valve 41; and into the ejection cylinder bore 13^a, and discharge port 42, the check valve 44 remaining closed during the charging of said cylinder and port under the influence of the spring 43, thereby forcing the ejection plunger 16, back toward the cam 22, where it remains until the working face or point of said cam strikes the plunger head 27, of said plunger 16, and drives said plunger forward against the charge, thereby discharging it through the discharge port 42; past the check valve 43, and into the discharge pipe from which the same quantity is discharged through a vaporizer, (not shown) and into the engine cylinder.

So long as the major axes of the eccentrics remain or run parallel with each other, the plunger strokes are coincident and therefore they reach the ends of their strokes at the same time and consequently a maximum charge is taken in and expelled. This is the position of the eccentrics shown in the drawing; to decrease the charge the gear 30, is shifted toward the right (as viewed in

Fig. 2) whereupon one of the shafts 18, 20, is retarded, and the other advanced, thereby changing the angular relation between the major axes of the eccentrics, and the shafts will continue to rotate in this changed relation so long as the gear is held in its new position. The effect of the advanced and retarded relation of the shafts 18, 20, is that one of the charging plungers reaches the ends of its strokes before the other one does; consequently, during the interval that the other plunger is finishing its stroke, the first one is on its return stroke and each plunger is counteracting the effect of the other. When the retarded plunger 80 has reached the end of its stroke and begins its return stroke, both become effective and during suction strokes take liquid into the cylinders and during discharge strokes expel it into the ejection cylinder. When the gear 30, is moved far enough to bring the major axes of the eccentrics 180 degrees apart from the position shown, one plunger neutralizes the action of the other and consequently no charge is taken in.

In modified form, illustrated in Fig. 4, diaphragms 15^b, are substituted for the plungers 15, 16, 17 of the preferred form, which may be operated by the scotch yokes and cam. In this form the liquid is drawn 95 into the diaphragms and expelled by expanding and contracting them in the usual manner.

The device has been illustrated for use on one cylinder, but when the engine has a plurality of cylinders, the pumping means may be multiplied accordingly and all operatively connected to the shafts 18, 19, 20, in accordance with the arrangement shown.

More or less variation of the exact details 105 of construction are possible without departing from the spirit of this invention; I desire, therefore, not to limit myself to the exact forms of the invention shown and described herein, but intend in the following 110 claims to point out all of the invention disclosed herein.

I claim as new and desire to secure by Letters Patent:—

1. A variable delivery pump and injector, 115 comprising in combination, two chambers in which the liquid is measured, plungers having fixed lengths of strokes reciprocating therein, means for reciprocating said plungers, controlling means for timing the 120 strokes of said plungers, an ejector chamber in communication with said measuring chambers having a valve controlled discharge port, a plunger in said ejector chamber and operating means for said plunger. 125

2. A variable delivery pump and injector, comprising in combination, two communicating charging cylinders having valve controlled inlet and discharge ports, plungers, one reciprocating in each cylinder, operat- 130

- ing means for reciprocating said plungers with constant strokes, means for varying the timing of said plungers, an ejection cylinder in communication with the discharge port of the charging cylinders, a plunger in said ejection cylinder, operating means therefor, and a valve controlled discharge port for said ejection cylinder.
3. A variable delivery pump and injector, comprising two charging cylinders, having valve controlled inlet and discharge ports, plungers, one reciprocating in each cylinder, operating means for said pistons, and controllable means for changing the timing of strokes of said plungers to vary the volume of liquid displaced, an ejector cylinder in communication with said charging cylinders, having a valve controlled discharge port, a plunger in said ejector cylinder, and operating means therefor.
4. A variable delivery pump and injector, comprising two charging cylinders, opening to a valve controlled inlet passage, a plunger in each cylinder, an ejector cylinder connecting with said inlet charging cylinders, and having a valve controlled discharge port, a plunger in said ejector cylinder, a main drive shaft, a cam thereon for actuating the ejector cylinder piston, two shafts driven from said first named shaft, eccentric connections between said two shafts and the charging cylinder plungers, and means for varying the angular relation between the eccentrics.
- 35 5. A variable delivery pump and injector, comprising in combination, two intercommunicating charging chambers, an ejector chamber in communication therewith, means for admitting a charge to each charging chamber and discharging it into the ejector chamber, means for varying the size of said charging chambers to thereby vary the volume of charge admitted, and comprising reciprocatory plungers having constant lengths of strokes, and means for discharging the charge from the ejector chamber.
6. A variable delivery pump and injector, comprising an inlet passage, two intercommunicating charging chambers and an ejector chamber communicating therewith, mechanism associated with said charging
- chambers comprising reciprocatory plungers therein having constant lengths of strokes, for delivering measured charges to said ejection chamber and means for ejecting 55 said measured charges from said ejection chamber.
7. A variable delivery pump and injector, comprising an inlet passage, two charging cylinders communicating therewith, reciprocating plungers in said cylinders, reciprocating mechanism for said plungers having correlated timing means, an ejector cylinder communicating with said inlet passage, a plunger therein movable in one direction under the influence of liquid pressure within its cylinder and plunger actuating means for said last mentioned plunger.
8. A variable delivery pump and injector, comprising two intercommunicating liquid measuring chambers, mechanism for charging said cylinders and discharging the contents from said cylinders, comprising two reciprocatory plungers therein having constant lengths of strokes, an ejector chamber 75 communicating with said charging chamber, mechanism for discharging the contents of said ejector chamber in timed relation to the charging cylinder mechanism.
9. A variable delivery pump and injector, comprising a valve controlled inlet passage, two charging cylinders communicating therewith, and an ejector cylinder communicating with said inlet passage, there being a check valve opening from said inlet passage to said ejector cylinder, and a valve 85 opening outward in the discharge passage of said ejector cylinder, plungers in said cylinders, three shafts, eccentric connections between two of said shafts and the plungers of the charging cylinders, a cam on the third shaft for actuating the plungers of the ejector cylinder, a right and left spiral toothed gear slidably connected with said third shaft, a right hand spiral toothed gear mounted on one of the other shafts and a left hand spiral toothed gear mounted on the other shaft in mesh with the right and left spiral toothed gear, and means for shifting said last mentioned gear on its shaft. 100

JOHN G. ZUBER.
